UNITED STATES PATENT OFFICE.

GEORGE F. AICHELE, OF FORT WAYNE, INDIANA.

DESIGN FOR A GRAVE-MARKER.

50,457.

Specification for Design.

Patented Mar. 20, 1917.

Application filed November 13, 1916. Serial No. 131,152. Term of patent 3½ years.

To all whom it may concern:

Be it known that I, GEORGE F. AICHELE, a citizen of the United States, residing at Fort Wayne, in the county of Allen and State of Indiana, have invented a new, original, and ornamental Design for Grave-Markers, of which the following is a specification, reference being had to the accompanying drawing, forming part thereof.

The figure is a perspective view of a head marker, showing my new design.

I claim:

The ornamental design for a grave marker as shown.

GEORGE F. AICHELE.

Witnesses:

MARIE A. HARTMAN,
MATILDA METTLER.
